(Cl. D22—3)

To all whom it may concern:

Be it known that we, Herschel O. Browne and Walter J. Klassen, citizens of the United States, residing at Kansas City, in the county of Jackson and State of Missouri, and Johnson County and State of Kansas, respectively, have invented a new, original, and ornamental Design for a Combined Cleaver and Meat Tenderizer, of which the following is a specification, reference being had to the accompanying drawing, forming a part thereof.

Fig. 1 is a perspective view of one side and edge of the combined cleaver and meat tenderizer, showing our new design, and

Fig. 2 is a perspective view of the opposite side and edge thereof.

We claim:

The ornamental design for a combined cleaver and meat tenderizer, as shown.

HERSCHEL O. BROWNE.

WALTER J. KLASSEN.
